UNITED STATES PATENT OFFICE.

WARREN F. FRASER, OF WESTBORO, MASSACHUSETTS.

GRINDER.

1,424,398.

Specification of Letters Patent. Patented Aug. 1, 1922.

Application filed May 8, 1920. Serial No. 379,843.

To all whom it may concern:

Be it known that I, WARREN F. FRASER, a citizen of the United States, residing at Westboro, in the county of Worcester and

5 State of Massachusetts, have invented new and useful Improvements in Grinders, of which the following is a specification.

This invention relates to improvements in grinders.

10 It is the object of the invention to provide a grinder particularly adapted for rapidly and accurately grinding large quantities of similarly shaped small parts, the said grinder being entirely controlled by the feet 15 of the operator, thereby leaving the hands of said operator free to be used solely for inserting and removing the work.

It is also an object of the invention to provide a novel mechanism for causing the 20 head-stock and tail-stock to grip and release the work simultaneously with the operation of a foot treadle which controls the rotation of the head-stock spindle, the downward movement of said foot treadle successively 25 disconnecting said spindle from its driving instrumentalities, then causing the chuck to release the work held thereby, and finally withdrawing the tail-stock centering pin in order that the work may be removed, the 30 upward movement of the treadle causing a reversal of said operations when the foot is removed from said treadle.

It is also an object of the invention to provide in conjunction with a foot treadle 35 for operating a clutch mechanism to throw into operation the grinding wheel feeding mechanism, means for automatically locking said clutch in engagement with the driving instrumentalities, and also means to automatically disconnect said driving instrumentalities at the completion of the grinding operation.

Another object of the invention is to eliminate the results of inaccuracies and lost motion which may occur in the grinding wheel feeding mechanism, and by so doing increase the accuracy and efficiency of the grinder.

Still another object of the invention is to

provide grinding wheel dressing instrumentalities which are movable with the grinding wheel and also adjustable relatively thereto.

The invention consists in the combination and arrangement of parts whereby the above objects and certain other objects hereinafter appearing may be attained as set forth in the following specification, and particularly pointed out in the claims thereof.

Referring to the drawings:

Figure 1 represents a front elevation of 60 a grinder embodying my invention.

Figure 2 is a vertical section taken on line 2—2 of Figure 1 as viewed from the right in said figure.

Figure 3 is a plan view of the head-stock mechanism, a portion of the same being illustrated in horizontal section taken upon the line 3—3 of Figure 1.

Figure 4 is a vertical longitudinal section 70 through the tail-stock.

Like numerals refer to like parts throughout the several views of the drawings.

In the drawings, 10 represents the main frame of the machine provided with a bed-plate 11 upon which are mounted a head-stock 12 and a tail-stock 13, each being adjustable longitudinally of said bed-plate and securely clamped thereto at any desired location thereon. A grinding wheel 14 is ro-

tatably mounted in a frame 15 which is secured to a carriage 16 adapted to reciprocate transversely of the bed-plate 11 upon another bed-plate 17 also forming a part of the frame 10. A driving shaft 18 is journaled to rotate in suitable bearings provided upon the frame 10 and is driven by a pulley 19 from any suitable source of power.

A cone pulley 20 is fast to the driving shaft 18 and is adapted to drive 85 by means of a belt 21 a cone pulley 22 which is loosely mounted upon a counter-shaft 23 journaled to rotate in bearings provided upon the frame 10 and in a bracket 24, the said bracket being supported upon said frame.

A pulley 25 is secured to and adapted to rotate with the cone pulley 22 and is connected by a cross belt 26 with an elongat-

ed pulley 27 which is fast to a shaft 28 mounted to rotate in bearings 29 and 30 provided in a frame 31 forming a part of the head-stock 12, see Figure 3.

5 A clutch member 32 provided with teeth 33 is fast to the shaft 28 and is also adapted to slide longitudinally on said shaft in order that the teeth 33 may engage teeth 34 of a clutch member 35 which is formed integral 10 with a spur gear 36 loosely mounted upon a reduced portion of the shaft 28. The spur gear 36 meshes with and drives a spur gear 37 fast to a spindle 38 journaled to rotate in bearings 39 and 40 which are supported 15 in the head-stock frame 31. The spindle 38 constitutes the driving member of the head-stock 12 and is driven continuously except when the clutch member 32 is disengaged from the clutch member 35 which is accomplished in the following manner:

Pivotedly mounted upon a stud 41 projecting from the frame 10 is a foot treadle 42 which is normally held in its uppermost position as illustrated in Figures 1 and 2, by a 25 spring 43. The foot treadle 42 is connected by a rod 44 with a cam lever 45 which is pivotally mounted upon a stud 46 fast to the head-stock frame 31. The cam lever 45 is provided with a cam surface 47 which engages a roll 48 carried by a lever 49 fast to a shaft 50 mounted to rock in bearings 51 and 52, also provided in the head-stock frame 31. Fast to the rock-shaft 50 is a clutch shifting arm 53 the upper end of 30 which is forked and provided with rolls 54 which are adapted to engage the sides of an annular groove 55 provided in the clutch member 32. A spring 56 encircles the rock-shaft 50, one end of said spring being fast 35 to said shaft and the other end fast to the head-stock frame 31, and always acts to force the clutch member 32 into engagement with the clutch member 35.

By placing a foot upon the treadle 42 the 45 cam lever 45 is rocked upon the stud 46 and the cam surface 47 will cause the lever 49 to rock the shaft 50 thereby rocking the shifting arm 53 and forcing the teeth 33 of the clutch member 32 out of engagement with 50 the teeth 34 of the clutch member 35. This will disconnect the spindle 38 from its driving instrumentalities whereupon it will immediately cease to rotate and will remain stationary until the foot is again removed 55 from the treadle 42.

As previously stated, one of the novel features of this invention is the mechanism whereby the work may be gripped and released by the head-stock 12 and tail-stock 13 60 simultaneously with the operation of the foot treadle 42. By referring to Figure 3, so much of this mechanism as is related to the head-stock 12 is as follows:

The spindle 38 is provided with a bore 57 65 which extends longitudinally therethrough

upon the axis thereof. Located within the bore 57 at the end adjacent to the tail-stock 13 is a spring chuck 58. The spring chuck 58 is formed with an enlarged frusto-conical outer end 59 which is adapted to fit a corresponding shaped opening 60 at the end of the bore 57. The outer end of the chuck 58 is provided with a recess 61 and a plurality of radial slots 62 which allow said chuck to grip the end of the work supported 75 therein.

The chuck 58 is adapted to slide longitudinally within the spindle 38 and also to rotate therewith, a pin 63 being provided in the spindle 38 which projects into a longitudinal groove 64 in said chuck. The inner end of the chuck 58 is screw threaded at 65 and has attached thereto a rod 66 which extends through the spindle 38 upon the axis thereof, projecting beyond the rear end 85 of said spindle and terminating with a hexagonal portion 67 at its extreme outer end. Fast to the rear end of the spindle 38 is a collar 68, and mounted upon the rod 66 near the rear end thereof is a similar collar 69. 90 A pair of rods 70 extend between the collars 68 and 69 being securely fastened to each and thereby positioning the collar 69 relatively to the rear end of the spindle 38. The rod 66 is provided with an enlarged portion 71 which is forced against the collar 69 if there is no work in the chuck 58, by a spring 72 which encircles the rod 66, opposite ends thereof bearing against the adjacent faces of the enlarged portion 71 and 100 collar 68, being compressed therebetween. The normal tendency of the spring 72, therefore, is to force the enlarged tapered end 59 of the chuck 58 inwardly against the tapered opening 60 at the end of the spindle 38 and thereby cause the chuck 58 to grip the work which is located within the recess 61. If there is no work in the chuck the collar 69 constitutes a stop to prevent the spring 72 from forcing the outer end of the chuck too 110 far into the opening 60 and thereby tending to bend the gripping portions of the chuck. A screw 71¹ located in the collar 69 projects into one of a plurality of slots 71² formed in the periphery of the member 71 thereby locking the rod 66 to the collar 69. As the spindle 38 rotates, the chuck 58, rod 66, collars 68 and 69, rods 70 and spring 72 will all rotate simultaneously therewith.

The spindle 38 is prevented from moving 120 longitudinally within the bearings 39 and 40 by a cap 73 which has screw threaded engagement with a boss 74 formed integral with the head-stock frame 31 and bears against a flange 75 formed integral with the 125 spindle 38, the said flange rotating between said cap 73 and a ring 76 which is inserted in an annular recess provided therefor in the boss 74 adjacent to the outer end of the bearing 40. The spring chuck 58 may 130

be removed from the spindle 38 by removing the screw 71¹ and then turning the rod 66 thereby forcing the chuck 58 outwardly.

The cam lever 45 is provided with a cam surface 77 which engages a cam roll 78 carried by a lever 79 mounted to rock upon a shaft 80, supported in suitable bearings 81 and 82 provided in the head-stock frame 31. An arm 83 formed integral with the lever 79 has adjustably fastened therein a stud 84 which is adapted to push against the end of the rod 66. Whenever a foot is placed upon the treadle 42, the rocking movement of the cam lever 45 not only disengages the spindle 38 from its driving instrumentalities as previously described, but also simultaneously rocks the lever 79 and thereby forces the rod 66 longitudinally within the spindle 38 and against the pressure of the spring 72 and causes the chuck 58 to ungrasp the work held thereby. The pressure of the stud 84 against the end of the rod 66 also acts to stop the momentum of the spindle 38. Upon removing the foot from the treadle 42 the spring 72 will again cause the chuck to grip the work and force the lever 79 back to its original position.

A stop pin 85 projecting from the head-stock frame 31 is located in a position to be engaged by the cam lever 45 and thereby limit the upward movement of the foot treadle 42. The head-stock frame 31, together with all the parts mounted thereon may be located at any position desired upon the bed-plate 11, being fastened thereto by a clamp rod 86, the lower end of which is located in a groove 87 which extends longitudinally in the bed-plate 11 and engages a flange formed integral with said bed-plate as illustrated in Figure 2.

Simultaneously with the operation of the foot treadle 42 and during the latter part of the downward movement thereof, the tail-stock mechanism 13 is also caused to be operated to withdraw the centering pin thereof in order that the work may be removed from between the head-stock and tail-stock. Referring particularly to Figures 1, 3 and 4, an arm 88 is loosely mounted upon the stud 46 and has a pin 89 projecting forwardly therefrom which is adapted to be engaged by an upper edge 90 of the cam lever 45 during the latter part of the movement thereof. The arm 88 is connected by a rod 91 with an arm 92 to which it is clamped, the arm 92, in turn, being fast to a shaft 93 mounted to rock in a frame 94 forming a part of the tail-stock 13. A spur gear 95 is fast to the rock-shaft 93 and is located within the recess 96 formed in the tail-stock frame 94. The gear 95 meshes with a rack 97 formed upon a sleeve 98, the axis of which is in longitudinal alignment with the axis of the spindle 38 of the head-stock 12. A centering pin 99 is se-

cured in the end of the sleeve 98 adjacent to the head-stock 12, the said pin cooperating with the chuck 58 in supporting the work which is located therebetween. The end of the sleeve 98, in which the centering pin 99 is located, projects through the frame 94 and has a cap 100 fast thereto, a portion thereof surrounding a boss which is formed integral with the tail-stock frame 94. The sleeve 98 is adapted to slide longitudinally within a bore 101. A spring 102 is located within the bore 101, one end of said spring bearing against the sleeve 98 and the other end against an adjusting screw 103 which has screw threaded engagement with a plug 104 located at the rear end of the tail-stock frame 94. The screw 103 is adapted to regulate the tension of the spring 102 and when properly adjusted is secured in position by a lock nut 105.

A handle 106 is formed integral with the arm 92 in order that the tail-stock mechanism may be operated independently of the foot treadle 42 if it is so desired. The tail-stock 13 may be located at any position desired upon the bed-plate 11, being fastened thereto by a clamp rod 107 in a manner similar to that employed in fastening the head-stock 12 previously described. In Figure 1 the tail-stock has been moved toward the end of the bed-plate 11 in order to more clearly illustrate the grinding instrumentalities which would otherwise be partially obscured.

During the latter part of the downward movement of the foot treadle 42, the upper edge 90 of the cam lever 45 will engage the pin 89, thereby rocking the arm 88 and transmitting through the rod 91 a rocking movement to the arm 92 which being fast to the shaft 93 will rock said shaft and spur gear 95 thereby moving the sleeve 98 and centering pin 99 toward the right, in Figures 1 and 4 against the tension of the spring 102. This will release the centering pin 99 from engagement with the work which can then be removed and replaced by other work. Upon again releasing the foot treadle 42, the spring 102 will immediately force the centering pin toward the left and once more into yielding engagement with the work which is thereafter gripped by the chuck 58 and the spindle again rotated as previously described.

The mechanism for controlling and operating the grinding instrumentalities is as follows: Pivotedly mounted upon the stud 41 adjacent to the foot treadle 42, is a second foot treadle 108 which is connected by a rod 109 with a horizontally disposed lever 110 fast to a shaft 111 mounted to rock in suitable bearings in the bracket 24. Also fast to the shaft 111 is a shifting arm 112 which is adapted to operate a movable clutch member 113 fast to the counter-shaft 23 and 130

force said clutch member into engagement with a second clutch member 114, thereby causing the counter-shaft 23 to rotate with the cone pulley 22. Fast to the counter shaft 23 at the outer end thereof is a brake-drum 115. A lever 116 is pivoted at 117 to the bracket 24, one end of said lever being connected by a link 118 to the lever 110 and the other end of said lever having a screw 119 mounted therein which is adapted to engage the lower end of a friction member 120 slidably mounted in a vertical position in the bracket 24, and force said friction member against the brake-drum 115 at such times as the counter-shaft 23 is disengaged from the cone pulley 22. Fast in the opposite end of the lever 110 from that to which the rod 109 is connected, is a pin 121, the upper side of said pin being semi-cylindrical and the under side being flattened. The pin 121 is adapted to engage an oppositely disposed correspondingly shaped pin 122, the upper side being flattened and the under side being semi-cylindrical, said pin being fast to the lower end of a vertically disposed lever 123 which is pivoted upon a stud 124 projecting from a bracket 125 attached to the front of the frame 10. A spring 126, one end of which is attached to the frame 10 and the other end attached to the long arm of the lever 110, always acts to pull said long arm downwardly and cause the flattened surface of the pin 121 to engage the flattened surface of the pin 122, thereby holding the clutch member 113 in clutching engagement with the clutch member 114 and also holding the friction member 120 out of engagement with the brake-drum 115. Fast to the counter-shaft 23 and rotatable therewith is a worm 127 which is adapted to drive a worm gear 128 fast to a shaft 129 mounted to rotate in bearings 130 and 131 provided upon the frame 10 and the bracket 125 respectively. Fast to the shaft 129 is a cylindrical cam 132 provided with a cam surface 133. A pin 134 is located in the front face of the cam 132, said pin being adapted to engage at the proper time a roll 135 attached to the lever 123 and force the upper end of said lever toward the right, Figure 1, against the action of a spring 136. This movement of the lever 123 will move the pin 121 attached at the lower end thereof, out of engagement with the pin 122 thereby allowing the spring 126 to disengage the clutch member 113 from the clutch member 114 and at the same time cause the friction member 120 to engage the brake drum 115 thereby preventing further rotation of the counter-shaft 23. At the upper end of the lever 123 is located a suitable handle 137 which may be utilized for manually disconnecting the counter-shaft 23 from its driving instrumentalities. A stop pin 138 projecting from the bracket 125 limits the move-

ment of the upper end of the lever 123 toward said bracket and positions the lower end of said lever in order that the pins 121 and 122 may engage each other at the proper time.

Pivoted to the bracket 125 at 139 is a lever 140 the lower end of which has a cam roll 141 attached thereto, which is adapted to engage the working cam surface 133 of the cylindrical cam 132. The upper end of the lever 140 is attached by a link 142 with the carriage 16 upon which is supported the frame 15 which, in turn, supports the grinding instrumentalities. The carriage 16 is mounted to reciprocate transversely of the bed plate 11 upon ways 143 and 144 provided upon the bed plate 17, which constitutes a part of the frame 10. The frame 15 is adjustably mounted to slide transversely of the bed plate 11 in ways 145 provided upon the carriage 16. The grinding wheel 14 is attached to a shaft 146 which is adapted to rotate in bearings 147 provided therefor upon the frame 15 and is driven continuously at a high rate of speed by a pulley 148 attached to the main driving shaft 20 through the medium of a belt 149 which extends around a pulley 150 attached to the shaft 146.

In order to compensate for the varying distance between the centers of the shafts 20 and 146 during the reciprocatory movement of the carriage 16, a belt tightening device is provided which consists of a bell-crank lever 151 which is pivoted upon a stud 152 projecting from the side of the arm 10. An arm 153 of the bell-crank lever 151 has an idler pulley 154 rotatably mounted thereon, while another arm 155 of the bell-crank lever 151 has a weight 156 attached thereto which is adapted to always force the idler pulley 154 against the belt 149 thereby causing said belt to properly grip the pulleys 148 and 150.

When the work is properly secured between the head-stock 12 and tail-stock 13, as previously described, and ready for the grinding operation, a foot is placed upon the foot treadle 108 forcing the same downwardly thereby simultaneously releasing the brake drum 115 and forcing the clutch member 113 into engagement with the clutch member 114 thereby causing the counter-shaft 23 to rotate. As the long arm of the lever 110 moves upwardly the semi-cylindrical upper side of the pin 121 will engage the rounded lower side of the pin 122, causing the lower end of the lever 123 to rock slightly and allow the pin 121 to pass the pin 122 after which the spring 136 will pull the lever 123 back into its normal position and the said pins will align with each other, the flattened faces thereof being in engagement with each other. This will prevent the spring 126 from rocking the lever

110 and disconnecting the counter-shaft 23 from its driving instrumentalities when the foot is removed from the treadle 128. The rotation of the counter-shaft 23 with the worm 127 fast thereto will drive the worm gear 129 and thereby rotate the cylindrical cam 132, the working cam surface 133 of which contacting with the cam roll 141 will rock the lever 140 upon its pivot 139 and move the carriage 16 toward the left, Figure 2, thereby moving the grinding wheel 14 into engagement with the work. During this time the grinding wheel 14 is being rotated continuously at a rapid rate of speed by the belt 149 from the pulley 148 fast to the main driving shaft 20. The carriage 16 with the grinding instrumentalities carried thereby are fed quickly toward the work during the initial movement of the cylindrical cam 132 but during the greater portion of the rotation of said cam, or, during the actual grinding period the carriage 16 moves very slowly and is not moved rearwardly until the cam has nearly completed one revolution, when a cam surface 133¹ will engage the roll 141 as illustrated in Figure 2 thereby returning the carriage 16 to its initial position. Just prior to the completion of the rotation of the cam 132, the pin 134 carried thereby will engage the roll 135 which is attached to the lever 123 forcing the upper end of said lever toward the right, in Figure 1, and rocking the lower end of said lever a sufficient distance to disengage the pin 122 from the pin 121, whereupon the spring 126 will automatically cause the lever 110 to rock and simultaneously disengage the counter-shaft 23 from its driving instrumentalities and cause the friction member 120 to grip the brake drum 116. This will prevent further rotation of the cam 132 and cause the carriage 16 to come to a rest at its extreme rearward position. The carriage 16 is always fed the same distance by the cam 132 irrespective of the diameter of the work upon which the grinding operation is performed. It is, therefore, necessary when changing the diameter of either the work or the grinding wheel 14, to adjust the location of the frame 15 upon the carriage 16 in order that when the grinding wheel has been fed into engagement with the work and the grinding operation has been completed that the work will have been accurately ground to the required diameter. The means for accomplishing this adjustment is as follows: Fast to the front of the frame 15 is a bracket 157 in which is rotatably mounted an adjusting screw 158 the rear end of which has screw threaded engagement with the carriage 16. Fast to the front end of the adjusting screw is a hand wheel 159 upon the periphery of which are suitable graduations 160 which represent preferably in thousandths of an inch the movement imparted to the frame 15 by the adjusting screw 158 when said screw is rotated. A finger 161 projects from the frame 15 and terminates in a position adjacent to the periphery of the hand wheel 159, the graduations 160 registering with said finger. In order to eliminate the results of inaccuracies and lost motion which may occur between the cam 132, lever 140, link 142 and carriage 16 during the feeding of said carriage and the grinding operation and thereby increase the accuracy of said operation, an adjustable stop is provided to limit the forward movement of the carriage 16. Fast to the rear of the frame 10 is a bracket 162 and projecting rearwardly from the carriage 16 and passing through an opening in the bracket 162 is a rod 163. A thumb nut 164 has screw threaded engagement with the rod 163 and is adapted to abut against the bracket 162. The thumb nut is provided with suitable graduations 165 which extend around the hub portion thereof and register with a suitable mark upon the bracket 162. The graduations 165 also represent in thousandths of an inch the movement of the carriage 16. A lock nut 166 also has screw threaded engagement with the rod 163 and is attached to the thumb nut 164 by screws 167 being rotatable with said thumb nut. In locating the thumb nut 164 upon the rod 163 the said nut is so positioned that during the forward movement of the carriage 16, the nut 164 will abut against the bracket 162 about .002" in advance of the actual forward position of the carriage, the lever 140 yielding enough to offset the distance lacking. The arrangement of the thumb nut 164 and lock nut 166 also eliminates any lost motion therebetween when the screws 167 are tightened to clamp said nuts upon the screw thread to prevent rotation thereof.

As previously stated one of the objects of the invention is to provide grinding wheel dressing instrumentalities which will be movable with the grinding wheel 14 and also adjustable relatively thereto. This device is constructed as follows: Mounted upon the grinding wheel frame 15 is a bracket 168 which is provided with vertical ways 169 upon which a slide 170 is mounted and adapted to be fed vertically by a feed screw 171. Fast to the upper end of the feed screw is a hand wheel 172 by which said screw is rotated, and also attached to the feed screw is a disc 173 upon the periphery of which are graduations 174 which are adapted to register with a mark upon a finger 175. The graduations 174 represent in thousandths of an inch the movement of the slide 170. Fast to the slide 170 is a cylinder 176 in which a tool holding member 177 is adapted to be moved longitudinally by a feed screw 178 which is rotatably mounted in a bearing 179 located at one end of said cylinder, said

feed screw being rotated by a hand wheel 180. The member 177 is prevented from rotating within the cylinder 176 by a suitable spline 181. Adjustably fastened in the member 177 is a grinding wheel dressing tool 182 which is provided with a diamond point 183 at the lower end thereof adapted to engage the periphery of the grinding wheel 14 and re-finish the surface thereof.

10 When the grinding wheel 14 requires redressing the hand wheel 172 is turned in the proper direction to lower the slide 170 slightly. A few thousandths of an inch is generally all that is necessary. The hand wheel 180 is then turned to move the tool holding member 177 with the dressing tool therein, across the periphery of the grinding wheel while said grinding wheel is rotating, thereby reducing slightly the diameter of said wheel and refinishing the surface thereof. After redressing the grinding wheel it is necessary to feed said wheel toward the work to compensate for the decrease in the diameter of said wheel in order that the next grinding operation will grind the work to the correct diameter. The hand wheel 159 is therefore turned a distance equal to that which the hand wheel 172 was turned to lower the slide 170, thereby moving the frame 15 and therefore the grinding wheel which is mounted thereon. It will therefore be seen that by locating the grinding wheel dressing instrumentalities in fixed relation to the grinding wheel, that 35 the mechanism for adjusting the frame 15 may co-operate with the vertical feeding mechanism of the grinding wheel dressing instrumentalities, thereby making it possible to quickly and accurately reposition 40 the grinding wheel after the same has been redressed.

The general operation of the grinder briefly described is as follows: When the foot treadle 42 has been forced downwardly by placing a foot thereon, the spindle 38 is first disconnected from its driving instrumentalities, the chuck 58 is then moved longitudinally in said spindle to ungripping position, during which time the momentum 50 of the spindle is stopped and finally the tail-stock centering pin 99 is moved longitudinally in the tail-stock 13 to a position where it will not interfere when the work is being inserted in position to be ground. With the 55 foot holding the treadle 42 at its lowermost position, one end of the work is inserted in the recess 61 of the chuck 58 and the foot is then removed from the treadle, whereupon the centering pin 99 will yieldingly engage the end of the work adjacent thereto, the chuck then grip the work and finally the spindle is again connected with its driving instrumentalities thereby causing the work to rotate. The work now being ready 60 to be ground, a foot is placed upon the 65

treadle 108 forcing it downwardly, thereby forcing the clutch member 113 into engagement with the clutch member 114 and connecting the counter-shaft 23, which has hitherto been remaining stationary, with its 70 driving instrumentalities. The foot may now be removed from the treadle 108 which is, however, still held in its lowermost position and prevented from moving upwardly by the pin 122 engaging the pin 121 and 75 thereby preventing any rocking movement of the lever 110 and the parts connected therewith. The rotation of the counter-shaft 23 will now be transmitted to the cylindrical cam 132 thereby rocking the 80 lever 140 and feeding the grinding wheel 14, which is rotating at a high rate of speed, into engagement with the work and will grind said work to the required diameter. At the completion of one rotation of the 85 cam 102, the pin 134 carried thereby will engage the roll 135 and rock the lever 123 thereby disengaging the pin 121 from the pin 122 and automatically disengaging the counter-shaft 23 from its driving instrumentalities, and also simultaneously applying the friction member 120 to the brake drum 115 thereby stopping the momentum 90 of the counter-shaft 23 and also simultaneously causing the foot treadle 108 to re- 95 turn to its initial position.

The grinding operation now being completed and all of the parts having returned to their initial positions, the work may be removed as previously described. It is evident that it is not necessary to use the chuck for gripping the work in order that said work may be rotated as the usual grinder dog may be employed in the well known manner if it is so desired. At such times 105 the mechanism for moving the chuck longitudinally in the spindle may be eliminated without departing from the spirit of this invention.

While in this embodiment of my invention 110 I have used the term "foot treadle" both in the specification and in the claims, it is evident that without departing from the spirit of my invention the foot treadle may be replaced by some other manually 115 operable member producing the same result, and it is to be understood in the following claims that the term "foot treadle" is to be read with this understanding.

Having thus described my invention, what 120 I claim and desire by Letters Patent to secure is:

1. A grinder having, in combination, 125 means to support work, means to rotate said work, a grinding wheel, means to support said grinding wheel, means to bring said work and said grinding wheel into operative engagement with each other, a manually operable member and means connected to said manually operable member adapted to 130

successively prevent the rotation of said work and release the work from operative engagement with its support.

2. A grinder having, in combination, 5 means to support work at opposite ends thereof, means to grip said work at one end thereof, means to rotate said gripping means, a grinding wheel, means to feed said grinding wheel into engagement with said work, and means to successively prevent the 10 rotation of said work, ungrasp one end of said work and remove the support from the other end of said work.

3. A grinder having, in combination, 15 means to support and grip work at one end thereof, means to center said work at the other end thereof, means to rotate said work, a grinding wheel, means to feed said grinding wheel into engagement with said work, 20 and means to successively prevent the rotation of said work, ungrasp one end of said work and remove the centering means from the other end of said work.

4. A grinder having, in combination, 25 means to support work at opposite ends thereof, means to grip said work at one end thereof, means to rotate said gripping means, a grinding wheel, means to feed said grinding wheel into engagement with said work, a foot treadle, and means connected to 30 said foot treadle adapted to successively prevent the rotation of said work, ungrasp one end of said work and remove the support from the other end of said work.

35 5. A grinder having, in combination, a head-stock and a tail-stock adapted to support and grip work therebetween, means to rotate said work, a grinding wheel, means to feed said grinding wheel into engagement 40 with said work, and means to successively stop the rotation of said work, cause said head-stock to release said work and remove said tail-stock from engagement with said work.

45 6. A grinder having, in combination, a head-stock and a tail-stock adapted to support and grip work therebetween, means to rotate said work, a grinding wheel, means to feed said grinding wheel into engagement 50 with said work, a foot treadle, and means operated by said foot treadle adapted to successively stop the rotation of said work, cause said head-stock to release said work and remove said tail-stock from engagement 55 with said work.

60 7. A grinder having, in combination, a head-stock and a tail-stock adapted to support and grip work therebetween, means to rotate said work, a grinding wheel, a carriage upon which said grinding wheel is mounted, means to impart a reciprocating motion to said carriage, a foot treadle, and means operated by said foot treadle adapted to successively stop the rotation of said 65 work, cause said head-stock to release said work and remove said tail-stock from engagement with said work.

work and remove said tail-stock from engagement with said work.

8. A grinder having, in combination, a head-stock and a tail-stock adapted to support and grip work therebetween, means to 70 rotate said work, a grinding wheel, a carriage upon which said grinding wheel is mounted, a cam adapted to impart a reciprocating motion to said carriage, means to rotate said cam, a foot treadle, and means 75 operated by said foot treadle adapted to successively stop the rotation of said work, cause said head-stock to release said work and remove said tail-stock from engagement with said work.

80 9. A grinder having, in combination, means to support and rotate work, a grinding wheel, means to support and rotate said grinding wheel, means to move one of said means toward the other of said means, and 85 means to positively limit said movement to the extent of springing the means by which said movement is accomplished.

10. A grinder having, in combination, a head-stock and a tail-stock adapted to support and grip work therebetween, means to 90 rotate said work, a grinding wheel, a carriage upon which said grinding wheel is mounted, a cam, means connecting said cam and said carriage adapted to impart a reciprocating motion to said carriage, a stop for said carriage adapted to eliminate the results of inaccuracies and lost motion between said cam and the connections to said carriage, means to rotate said cam, a foot 95 treadle, and means operated by said foot treadle adapted to successively stop the rotation of said work, cause said head-stock to release said work and remove said tail-stock from engagement with said work.

100 11. A grinder having, in combination, a head-stock and a tail-stock adapted to support and grip work therebetween, means to rotate said work, a grinding wheel, a carriage upon which said grinding wheel is 110 mounted, a cam, means connecting said cam and said carriage adapted to impart a reciprocating motion to said carriage, a stop for said carriage adapted to eliminate the results of inaccuracies and lost motion between said cam and the connections to said carriage and embodying therein a bracket provided with a mark thereon, a rod projecting from said carriage through said bracket, an adjusting nut on said rod provided with graduations thereon adapted to 115 co-operate with the mark upon said bracket, and means to lock said adjusting nut to said rod; means to rotate said cam, a foot treadle, and means operated by said foot treadle 120 adapted to successively stop the rotation of said work, cause said head-stock to release said work and remove said tail-stock from engagement with said work.

12. A grinder having, in combination, a 125

130

- head-stock and a tail-stock adapted to support and grip work therebetween, means to rotate said work, a grinding wheel, a carriage upon which said grinding wheel is mounted, a cam adapted to impart a reciprocatory motion to said carriage, means to rotate said cam embodying therein driving instrumentalities and a clutch mechanism, a pair of foot treadles, means connected with one of said foot treadles adapted to lock said clutch mechanism in engagement with said driving instrumentalities, and means connected with the other of said foot treadles adapted to prevent the rotation of said work.
- 10 13. A grinder having, in combination, a head-stock and a tail-stock adapted to support and grip work therebetween, means to rotate said work, a grinding wheel, a carriage upon which said grinding wheel is mounted, a cam, means to rotate said cam, means connecting said cam and said carriage adapted to impart a reciprocatory movement to said carriage, means to positively limit said movement to the extent of 15 20 25 30 35 40 45 50 55 60 65 70 75 80 85 90 95 100 105 110 115 120 125 130
14. A grinder having, in combination, a head-stock and a tail-stock adapted to support and grip work therebetween, means to rotate said work, a grinding wheel, a carriage upon which said grinding wheel is mounted, a cam adapted to impart a reciprocatory motion to said carriage, means to rotate said cam embodying therein driving instrumentalities and a clutch mechanism, a foot treadle, and means connected with said foot treadle adapted to lock said clutch in engagement with said driving instrumentalities.
15. A grinder having, in combination, a head-stock and a tail-stock adapted to support and grip work therebetween, means to rotate said work, a grinding wheel, a carriage upon which said grinding wheel is mounted, a cam adapted to impart a reciprocatory motion to said carriage, means to rotate said cam embodying therein driving instrumentalities and a clutch mechanism, a foot treadle, means connected with said foot treadle adapted to lock said clutch mechanism in engagement with said driving instrumentalities, and means to automatically disconnect said clutch mechanism from said driving instrumentalities at the completion of the grinding operation, and means connected to the other of said foot treadles adapted to successively prevent the rotation of said work ungrip one end of said work and remove the support from the other end of said work.
16. A grinder having, in combination, a head-stock and a tail-stock adapted to support and grip work therebetween, means to
- rotate said work, a grinding wheel, a carriage upon which said grinding wheel is mounted, a cam adapted to impart a reciprocatory motion to said carriage, means to rotate said cam embodying therein driving instrumentalities and a clutch mechanism, a pair of foot treadles, means connected to one of said foot treadles adapted to lock said clutch mechanism in engagement with said driving instrumentalities, and means connected with the other of said foot treadles adapted to prevent the rotation of said work.
17. A grinder having, in combination, a head-stock and a tail-stock adapted to support and grip work therebetween, means to rotate said work, a grinding wheel, a carriage upon which said grinding wheel is mounted, a cam adapted to impart a reciprocatory motion to said carriage, means to rotate said cam embodying therein driving instrumentalities and a clutch mechanism, a pair of foot treadles, means connected to one of said foot treadles adapted to lock said clutch mechanism in engagement with said driving instrumentalities, and means connected to the other of said foot treadles adapted to successively prevent the rotation of said work, ungrip one end of said work, and remove the support from the other end of said work.
18. A grinder having, in combination, a head-stock and a tail-stock adapted to support and grip work therebetween, means to rotate said work, a grinding wheel, a carriage upon which said grinding wheel is mounted, a cam adapted to impart a reciprocatory motion to said carriage, means to rotate said cam embodying therein driving instrumentalities and a clutch mechanism, a pair of foot treadles, means connected to one of said foot treadles adapted to lock said clutch mechanism in engagement with said driving instrumentalities, means to automatically disconnect said clutch mechanism from said driving instrumentalities at the completion of the grinding operation, and means connected to the other of said foot treadles adapted to successively prevent the rotation of said work ungrip one end of said work and remove the support from the other end of said work.
19. A grinder having, in combination, a head-stock and a tail-stock adapted to support and grip work therebetween, means to rotate said work, a grinding wheel, means to rotate said grinding wheel, a carriage, a frame upon said carriage in which said grinding wheel is rotatably mounted, means to move said frame relatively to said carriage, a cam adapted to impart a reciprocatory motion to said carriage, means to rotate said cam embodying therein driving instrumentalities and a clutch mechanism, a pair of foot treadles, means connected to one of

- 5 said foot treads adapted to lock said clutch mechanism in engagement with said driving instrumentalities, means to automatically disconnect said clutch mechanism from said 5 driving instrumentalities at the completion of the grinding operation, and means connected to the other of said foot treads adapted to successively prevent the rotation of said work, ungrasp one end of said work and remove the support from the other end of said work.
- 10 20. A grinder having, in combination, a head-stock and a tail-stock adapted to support and grip work therebetween, means to 15 rotate said work, a grinding wheel, means to rotate said grinding wheel, a carriage, a frame upon said carriage in which said grinding wheel is rotatably mounted, means to move said frame relatively to said carriage, a cam adapted to impart a reciprocatory motion to said carriage, means to rotate said cam embodying therein a counter-shaft, driving instrumentalities loosely mounted upon said counter-shaft, a brake drum fast 20 to said counter-shaft and a clutch mechanism; a friction member, a pair of foot treads, means connected to one of said foot treads adapted to lock said clutch mechanism in engagement with said driving instrumentalities, means to automatically disconnect 25 said clutch mechanism from said driving instrumentalities and apply said friction member to said brake drum at the completion of the grinding operation, and 30 means connected to the other of said foot treads adapted to successively prevent the rotation of said work, ungrasp one end of said work and remove the support from the other end of said work.
- 35 40 21. A grinder having, in combination, a head-stock and a tail-stock adapted to support and grip work therebetween, means to rotate said work, a grinding wheel, means to rotate said grinding wheel, a carriage, a frame upon said carriage in which said grinding wheel is rotatably mounted, means to move said frame relatively to said carriage, a cam adapted to impart a reciprocatory motion to said carriage, means to rotate said cam embodying therein a counter-shaft, driving instrumentalities loosely mounted upon said counter-shaft, a brake drum fast to 45 said counter-shaft and a clutch mechanism; a friction member, a rock-shaft, a horizontally disposed lever attached to said rock-shaft, a shifting arm also attached to said rock-shaft, a vertically disposed lever, a pair of foot treads one of which is connected to said horizontal lever and adapted to force said horizontal lever into locking engagement with said vertical lever and thereby hold said clutch mechanism in engagement with said driving instrumentalities, means to connect said friction member with said horizontally disposed lever, means to disconnect said horizontal and vertical levers and thereby automatically disconnect 50 said clutch mechanism from said driving instrumentalities and also force said friction member against said brake drum, and means connected to the other of said foot treads adapted to successively prevent the rotation of said work, ungrasp one end of said work and remove the support from the other end of said work.
- 55 60 22. A grinder having, in combination, a head-stock and a tail-stock adapted to support and grip work therebetween, means to rotate said work, a grinding wheel, means to rotate said grinding wheel, a carriage, a frame upon said carriage in which said grinding wheel is rotatably mounted, means to move said frame relatively to said carriage, a cam adapted to impart a reciprocatory motion to said carriage, means to rotate said cam embodying therein a counter-shaft, driving instrumentalities loosely mounted upon said counter-shaft, a brake drum fast to 65 said counter-shaft and a clutch mechanism; a friction member, a rock-shaft, a horizontally disposed lever attached to said rock-shaft, a vertically disposed lever, a pair of foot treads one of which is connected to said horizontal lever and adapted to force said horizontal lever into locking engagement with said vertical lever and thereby hold said clutch mechanism in engagement with said driving instrumentalities, means to connect said friction member with said horizontally disposed lever, means to disconnect said horizontal and vertical levers and thereby automatically disconnect 70 said clutch mechanism from said driving instrumentalities and also force said friction member against said brake drum, and means connected to the other of said foot treads adapted to successively prevent the rotation of said work, ungrasp one end of said work and remove the support from the other end of said work.
- 75 80 23. A grinder having, in combination, a head-stock and a tail-stock adapted to support and grip work therebetween, means to rotate said work, a grinding wheel, means to rotate said grinding wheel, a carriage, a frame upon said carriage in which said grinding wheel is rotatably mounted, means to move said frame relatively to said carriage, a cam adapted to impart a reciprocatory motion to said carriage, means to rotate said cam embodying therein a counter-shaft, driving instrumentalities loosely mounted upon said counter-shaft, a brake drum fast to 85 said counter-shaft and a clutch mechanism; a friction member, a rock-shaft, a horizontally disposed lever attached to said rock-shaft, a shifting arm also attached to said rock-shaft, a vertically disposed lever, a pair of foot treads one of which is connected to said horizontal lever and adapted to force said horizontal lever into locking engagement with said vertical lever and thereby hold said clutch mechanism in engagement with said driving instrumentalities, means to connect said friction member with said horizontally disposed lever, means to disconnect said horizontal and vertical levers and thereby automatically disconnect 90 said clutch mechanism from said driving instrumentalities and also force said friction member against said brake drum, and means connected to the other of said foot treads adapted to successively prevent the rotation of said work, ungrasp one end of said work and remove the support from the other end of said work.
- 95 100 24. A grinder having, in combination, a head-stock and a tail-stock adapted to support and grip work therebetween, means to rotate said work, a grinding wheel, means to rotate said grinding wheel, a carriage, a frame upon said carriage in which said grinding wheel is rotatably mounted, means to move said frame relatively to said carriage, a cam adapted to impart a reciprocatory motion to said carriage, means to rotate said cam embodying therein a counter-shaft, driving instrumentalities loosely mounted upon said counter-shaft, a brake drum fast to 105 said counter-shaft and a clutch mechanism; a friction member, a rock-shaft, a horizontally disposed lever attached to said rock-shaft, a vertically disposed lever, a pair of foot treads one of which is connected to said horizontal lever and adapted to force said horizontal lever into locking engagement with said vertical lever and thereby hold said clutch mechanism in engagement with said driving instrumentalities, means to connect said friction member with said horizontally disposed lever, means to disconnect said horizontal and vertical levers and thereby automatically disconnect 110 said clutch mechanism from said driving instrumentalities and also force said friction member against said brake drum, and means connected to the other of said foot treads adapted to successively prevent the rotation of said work, ungrasp one end of said work and remove the support from the other end of said work.
- 115 120 25. A grinder having, in combination, a head-stock and a tail-stock adapted to support and grip work therebetween, means to rotate said work, a grinding wheel, means to rotate said grinding wheel, a carriage, a frame upon said carriage in which said grinding wheel is rotatably mounted, means to move said frame relatively to said carriage, a cam adapted to impart a reciprocatory motion to said carriage, means to rotate said cam embodying therein a counter-shaft, driving instrumentalities loosely mounted upon said counter-shaft, a brake drum fast to 125 said counter-shaft and a clutch mechanism; a friction member, a rock-shaft, a horizontally disposed lever attached to said rock-shaft, a shifting arm also attached to said rock-shaft, a pin located at one end of said horizontal lever, a vertically disposed lever, a pin located at the lower end of said vertically disposed lever, a pair of foot treads, one of which is connected to 130

said horizontal lever and adapted to force the pin of said horizontal lever into locking engagement with the pin of said vertical lever and thereby hold said clutch mechanism in engagement with said driving instrumentalities, a pin attached to said cam and adapted to engage said vertical lever at the completion of the grinding operation to disconnect the pins carried by said horizontal and vertical levers and thereby automatically disconnect said clutch mechanism from said driving instrumentalities and also force said friction member against said brake drum, and means connected to the other of said foot treadles adapted to successively prevent the rotation of said work, ungrip one end of said work and remove the support from the other end of said work.

24. A grinder having, in combination, means to grip and support the work at one end thereof, means to rotate said work, a grinding wheel, means to feed said grinding wheel into engagement with said work, a manually operable member and means connected to said manually operable member adapted to successively prevent the rotation of said work and release the work from operative engagement with its support. 20
